[57] CLAIM

The ornamental design for a combined pillowcase and head covering, as shown and described.

DESCRIPTION

FIG. 1 is a top plan view of a combined pillowcase and head covering showing my new design; and FIG. 2 is a perspective view showing the combined pillowcase and head covering with the head covering portion raised for use.

The grid pattern on the head covering portion indicates fabric which contrasts with that of the rest of the pillowcase.

U.S. Patent
